US0D1056951S

(12) United States Design Patent (10) Patent No.: US D1,056,951 S
(45) Date of Patent: * Jan. 7, 2025

(54) DISPLAY SCREEN OR PORTION THEREOF WITH ICON

(71) Applicant: SHANGHAI RUIYU BIOTECH CO., LTD., Shanghai (CN)

(72) Inventor: Rui Chen, Shanghai (CN)

() Term: 15 Years

(21) Appl. No.: 35/519,582

(22) Filed: Jan. 5, 2023

(80) Hague Agreement Data

Int. Filing Date: Jan. 5, 2023

Int. Reg. No.: DM/226552

Int. Reg. Date: Jan. 5, 2023

Int. Reg. Pub. Date: Jan. 5, 2024

(51) LOC (15) Cl. 14-04

(52) U.S. Cl.

USPC D14/490

Primary Examiner — Katherine A Holbrow

Assistant Examiner — Erin F. Keister

(57) CLAIM

The ornamental design for a display screen or portion thereof with icon as shown and described.

DESCRIPTION

1: Front

The COUNT STAR™ logo, forming part of the claimed design, is a trademark of Shanghai RuiYu Biotech Co., Ltd. The outer perimeter shown in a pair of broken lines in the drawings illustrates a display screen or portion thereof and forms no part of the claimed design; the dot-dash broken lines define the boundary of the claimed design and form no part of the claimed design.

1 Claim, 1 Drawing Sheet
